US00D902664S

(12) **United States Design Patent** (10) Patent No.: **US D902,664 S**
(45) Date of Patent: **** Nov. 24, 2020**

(54) **BACKPACK COOLER**

(71) Applicant: **YETI Coolers, LLC**, Austin, TX (US)

(72) Inventors: **Jeffrey Charles Munie**, Austin, TX (US); **Kyle Edward Rogers**, Austin, TX (US); **Donald Edward Desroches**, Austin, TX (US); **John Loudenslager**, Austin, TX (US); **Derek G. Sullivan**, Austin, TX (US); **Alex Baires**, Austin, TX (US)

(73) Assignee: **YETI Coolers, LLC**, Austin, TX (US)

(**) Term: **15 Years**

(21) Appl. No.: **29/686,649**

(22) Filed: **Apr. 5, 2019**

Related U.S. Application Data

(63) Continuation of application No. 29/624,134, filed on Oct. 30, 2017, now Pat. No. Des. 848,219.

(57) **CLAIM**

The ornamental design for a backpack cooler, as shown and described.

DESCRIPTION

FIG. 1 is a top, front, right perspective view of a backpack cooler showing our new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof; and,

FIG. 8 is a top, rear, left perspective view thereof.

The even-length broken lines within the shaded area represent unclaimed stitching. The even-length broken lines showing the remainder of the backpack cooler represent unclaimed subject matter and form no part of the claimed design.

1 Claim, 8 Drawing Sheets
